UNITED STATES PATENT OFFICE.

WALTER H. BAKER, OF ST. LOUIS, MISSOURI, ASSIGNOR TO THE NATIONAL LEAD COMPANY, OF SAME PLACE.

DESIGN FOR A METAL INGOT.

SPECIFICATION forming part of Design No. 28,455, dated April 5, 1898.

Application filed January 24, 1898. Serial No. 667,828. Term of patent 14 years.

To all whom it may concern:

Be it known that I, WALTER H. BAKER, a citizen of the United States, residing at the city of St. Louis, in the State of Missouri, have ⁵ invented and produced a certain new and original Design for a Metal Ingot, of which the following is a full, clear, and exact description, reference being had to the accompanying drawings, forming part of this specification.

Figure I is a perspective view of the under side and edge of my design. Fig. II shows the design in section. Fig. III shows the design in elevation.

As shown in the drawings, the leading or ¹⁵ material features of my design consist of an ingot having one plane face 1, a convex face 2, and an intermediate peripheral edge 3. The edge 3 is circular in form and is regular throughout from the plane face 1 to the ²⁰ convex face 2.

I claim as my invention—
A design for a metal ingot substantially as herein shown and described.

WALTER H. BAKER.

In presence of—

E. S. KNIGHT,
STANLEY STONER.
